UNITED STATES PATENT OFFICE.

ANDREW J. EARLY, OF MERRIMAC MINES, VIRGINIA.

LOCK.

1,203,509.

Specification of Letters Patent. Patented Oct. 31, 1916.

Application filed May 26, 1915. Serial No. 30,705.

To all whom it may concern:

Be it known that I, ANDREW J. EARLY, a citizen of the United States, residing at Merrimac Mines, in the county of Montgomery and State of Virginia, have invented certain new and useful Improvements in Locks; and I do hereby declare the following to be a full, clear, and exact description of the invention, such as will enable others skilled in the art to which it appertains to make and use the same.

This invention relates to locks and has for its primary object to provide a lock especially designed for use in connection with doors and including a pivoted latch element and key controlled means for locking the latch element in locked position.

Another object is the provision of novel and efficient means for actuating the lock from either side of the door.

With these and other objects in view, the invention consists in the novel construction, arrangement and formation of parts as will be hereinafter specifically described, claimed and illustrated in the accompanying drawing, in which:

Figure 1 represents a front elevation of the improved lock, illustrating the same applied to use upon a door. Fig. 2 represents a top plan view of the lock, illustrating the door in section. Fig. 3 represents a side elevation of the lock. Fig. 4 represents a vertical central sectional view therethrough. Fig. 5 represents a side elevation, partly in section, of the locking element for the latch element removed. Fig. 6 represents a perspective view of the latch element removed from the casing, and Fig. 7 represents a side elevation of the key removed.

Referring to the drawing in detail, wherein similar reference numerals designate corresponding parts throughout the several views, the numeral 10 indicates generally the casing of the lock, which is preferably provided with a removable front or cover plate 11 and the side walls thereof are formed with apertures rotatably receiving a shaft 12 forming part of the latch element which also includes an enlarged end 13 having an angular extension 14 provided with a head 15. The angular end 14 of the latch element is disposed exteriorly of the casing 10 and carries a relatively non-rotatable plate 16 disposed within the casing and adapted to engage the front and rear walls of the latter to limit the rocking movement

of the shaft 12 and the angular latch arm 14. A spring 17 is suitably secured in the casing 10 and is engaged at its free end with the plate 16 below the shaft 12 and normally retains the latch arm 14 in downwardly extended or locked position.

Recesses 18 are formed in the upper and lower edges of the plate 16 and pivot pins 19 are secured to the side walls thereof and pivotally secure push rods 20 which project oppositely through the front and rear walls of the casing 10, and, are adapted, when pushed inwardly to swing the plate 16 and shaft 12 and lift the latch arm 14 from engagement with the keeper 21. Handles 22 are secured to the cover plate 11 of the casing and the opposite surface of the door 23, to which the casing is secured, and are provided with apertures slidably receiving the push rods 20. Knobs or other suitable type of handles 24 are secured to the free ends of the push rods 20, whereby the latter may be conveniently actuated.

A locking element or tumbler 25 is rotatably mounted in the front and rear walls of the casing 10 laterally of the lower portion of the plate 16 and is provided with a lateral enlargement 26, adapted to engage beneath the lower edge of the plate 16 to lock the latter against swinging movement when the latch arm 14 is engaged beneath the keeper 21. The tumbler 25 is controlled by a key 27 adapted to be inserted in either of the recesses 28 formed in the opposite ends of the body of the tumbler 25. The tumbler is frictionally held in adjusted position by the tension of a spring 29, the free ends of which are secured at 30 to the casing 10 and the medial portion is looped about and frictionally engaged with the lateral projection or enlargement 26.

A locking bar 32 is pivotally secured at 33 to the cover plate 11 and is provided with a notch 34 in its free end adapted to receive the enlarged extremity 13 of the locking element to lock the latter against rotational movement.

What I claim is:

1. A lock including a casing, a plate mounted in said casing, a shaft rotatably mounted in said casing extending through the longitudinal center of said plate and non-rotatably secured thereto, one end of said shaft being enlarged and directed angularly to provide a latch arm, a head on said latch arm, a pair of oppositely directed push

rods pivotally secured to said plate and extending exteriorly of said casing, means normally retaining said latch arm in locked position, and key controlled means for locking said latch element in locked position.

2. A lock including a casing, a plate arranged in said casing, a shaft rotatably mounted in said casing, extending through the longitudinal center of said plate and being non-rotatably secured to the latter, one end of said shaft exteriorly of said casing being enlarged to provide a latch arm, a head on said latch arm, push rods connected with said plate and extending exteriorly of

said casing, a tumbler rotatably mounted in said casing at right angles to said shaft having a lateral enlargement adapted, when swung inwardly, to engage behind said plate to lock the latter in adjusted position, and a spring loop secured to said casing engaged about the enlarged portion of said tumbler for retaining the latter in adjusted position.

In testimony whereof I affix my signature in presence of two witnesses.

ANDREW J. EARLY.
